[57] CLAIM

The ornamental design for a motorcycle tire, as shown and described.

DESCRIPTION

FIG. 1 is a perspective view of a motorcycle tire according to the present invention showing the tread pattern and configuration;

FIG. 2 is a front view of the tire of FIG. 1 it being understood that the back view is the same; and,

FIG. 3 is a side view of the tire of FIG. 1 it being understood that the other side is the same.

The tread pattern is understood to be repeated uniformly throughout the circumference of the tire and the opposite is the same as that shown.
